UNITED STATES PATENT OFFICE.

JOHN J. SENGLAR, OF TALLMADGE, OHIO, ASSIGNOR TO THE FIRESTONE STEEL PRODUCTS COMPANY, OF AKRON, OHIO, A CORPORATION OF OHIO.

LUG-MAKING PRESS.

Application filed April 24, 1925. Serial No. 25,592.

This invention relates to presses for progressively making lugs or the like, such as are riveted onto demountable wheel rims for use in securing the latter on wheels, 5 from a strip of metal of suitable form in cross-section.

The general object of the invention is to provide a pair of relatively movable press platens, carrying means for positioning the work therein, means for clamping the work in position therein, and a plurality of means simultaneously operable on the work, one to punch the bolt hole for the lug in the work, another to punch out a portion of one edge 15 of the work to provide rivets on the lug, and another to punch the lugs out of the work.

A particular object of the invention is to provide an improved work clamping device.

Another object is to provide an improved punch device for cutting a notch in an edge of a bar at an angle to said edge.

Another object is to provide a highly effective die construction for use in forming lugs from a bar of metal.

The foregoing and other objects are obtained by the construction illustrated in the accompanying drawings and described in detail below. It is to be understood that the invention is not limited to the specific construction shown and described.

Of the accompanying drawings:

Figure 1 is a plan of the lower platen 35 of a press embodying the invention;

Figure 2 is a side elevation of said press;

Figure 3 is a section on line 3-3 of Figure 1;

Figure 4 is a section on line 4-4 of 40 Figure 1;

Figure 5 is a section on line 5-5 of Figure 1;

Figure 6 illustrates in plan the strip from 45 which the lugs are being formed at any time during operation of the press; and

Figure 7 is a plan of the completed lug.

The lugs, one of which is shown in Figure 7, adapted for attachment to vehicle wheel rims are provided with a bolt aperture 50 10, rivets 11, 11 and a shoulder 12 for seating against the under side of the rim, the latter accordingly being formed on an angle, and the rivets 11 being perpendicular to said shoulder so that the lug proper will

be disposed vertically on the wheel rim and 55 the aperture 10 horizontally. A strip of metal indicated at 12^a (Figure 6) is accordingly formed with the cross-section shown in Figures 3, 4 and 5 to be supplied to the lug-forming press of the invention. 60

Briefly described, the press includes an upper platen 13 and lower platen 14, relatively movable with respect to each other. As best shown in Figures 1 and 2, the work is positioned in the press by a stop plate 15 on platen 14, the plate 15 being adjustable longitudinally of the press by means of a screw 16 journaled on platen 14 and threaded through a lug 17 formed on plate 15, plate 15 accordingly being adapted to 70 engage the end of the bar 12^a which is manually urged into the press between each operation thereof.

For guiding the bar into proper position in the press and for clamping it securely 75 during the operation of the press, a pair of clamping members 18 and 19 are mounted on platen 14, the member 19 being arranged above the member 18 is slidable on posts 19^a, 19^b and is normally held separated from member 18 by springs 20, 20. As shown in Figure 3, plates 18 and 19 are formed with longitudinal grooves of the profiles respectively of the upper and lower surfaces of the bar 12^a whereby they will snugly 85 fit about the bar when clamped thereon, the grooves also serving to guide the bar in proper relation to the various lug forming instrumentalities.

The first operation, namely punching the 90 bolt hole 10 through the lug, is adapted to be accomplished through the clamping members 18 and 19, the former having an aperture 21 through which a die 22, seated on platen 14, projects and the latter having an 95 aperture 23 through which a punch 24, carried by platen 13, is operable toward die 22. An aperture 25 is provided in platen 14 for conducting slugs, indicated at 26, from die 22. The die 22 is held in place 100 on platen 14 by a set screw 27 and the punch 24 is held in place on platen 13 by a clamping plate 28 and screws 28^a.

The plates 18 and 19 are arranged to be 105 yielding urged together during operation of the platens 13 and 14 toward each other by mounting on clamping plate 19 a pan 29 containing a resilient pad 30, preferably

of rubber, the pad being of a height greater than but of length and width less than the pan 29 and supported therein in spaced relation to its walls by lugs 31, 31 whereby the rubber of the pad can flow laterally when under compression, due to pressure of platen 13 on the pad.

For performing the second operation of notching one edge of bar 12^a to provide rivets on the finishing clamp, the platens 13 and 14 are equipped, as shown in Figure 4, with devices aligned longitudinally with respect to the above described punch and die. These devices include a die 32 including parts 32^a and 32^b mounted on platen 14 and over which bar 12^a passes and which is provided with an aperture 33 in communication with an aperture 34 through platen 14 through which slugs, indicated at 35, may pass from the press. An abutment member 36, for a purpose later to be explained, is mounted on platen 14 with die 32, the die 32 and member 36 being secured in a socket 37 in platen 14 by means of a wedge 38 engaging member 36 and urged inwardly of socket 37 by a cap screw 39, and also by a wedge block 57 later described.

On the platen 13, there is arranged a punch construction including a bracket 40 formed with a tongue 41 clamped in platen 13 by a plate 42 operable by screws 42^a threaded into the platen 13. The bracket 40 has pivoted thereon at 43 punch 44 operable along the arc of a circle by means of an arm 45 formed thereon and adapted to engage the abutment member 36 as platens 13 and 14 are moved together to cause punch 44 to take an arc-shaped cut out of one side of bar 12^a flush with the shoulder 12 thereon.

In order that wear of the punch 44, abutment 36 and die 32 may be compensated for to secure an accurate cutting by the punch 44, suitable shims, indicated at 46, at 47 and at 48, are provided.

For the final operation of shearing the lugs from bar 12^a, the devices, best shown in Figures 1 and 5, are provided. These are arranged in alignment with the above described devices longitudinally of the press, as will be understood. On platen 14 there is arranged a three part die (Figure 1) including die elements 49, of horseshoe shape in plan, 50 of rectangular shape in plan, and 51 of irregular shape, such as in cooperation with the other two members will complete the die opening 52. The parts 49, 50 and 51 are seated in a socket 53 in platen 14 and are clamped in place against adjacent walls thereof by wedge plates 54 and 55 engaged respectively by wedges 56 and 57 arranged in socket 53 and operable respectively by screws 58 and 59 threaded through platen 14. In practice, die members 49 and 50 are subject to great wear and die member 51 to little. Accordingly by the three

part construction, only those parts of the die which are worn need be removed and reground or replaced.

Cooperating with die elements 49, 50 and 51 is a punch 60 secured on upper platen 70 13 by a clamping plate 61 and screws 61^a, 61^b having a shearing edge 62 shaped to the upper surface of bar 12 and having a centering pin 63 adapted to pass through aperture 10 and removably secured in the punch by a set screw 64. Platen 14 is formed with an aperture 65 therein through which the completed lug is conducted from the press.

Overlying the platen 14 between the die 32 and the die elements 49, 50 and 51, there is arranged a stripper plate 70 formed so that bar 12^a may pass thereunder (Figure 4) between the above dies.

As best shown in Figure 1, the platen 14 is provided with a surface 66 sloping downwardly from die member 49 so that the triangular slugs 67, 67 of the metal between the lugs punched from bar 12^a will slide down surface 66 and through an aperture 68 in platen 14 from the press.

In operation, it will be understood that bar 12^a will be slid between members 18 and 19 into abutment with stop plate 15. At each operation of the platens, the hole 10 will be punched at point A on the bar 12^a (Figure 6) by punch 24 and die 22, the notch between rivets 11 will at the same time be punched by pivotal punch member 44 and die 32 at point B on bar 12, no operation will be performed at point C, and finally the lug will be punched out of the bar by punch 60 and die members 49, 50 and 51 at point D on the bar 12, the resulting lug being shown in Figure 7.

It will appear from the foregoing that three operations are performed simultaneously at each operation of the press, the bar 12 being fed forwardly against stop 15 between each operation, and a lug being delivered by the press after each operation thereof.

Modifications of the invention may be resorted to without departing from the spirit thereof or the scope of the appended claims.

What is claimed is:

1. In a punch press including relatively movable platens, work clamping means including a pair of plates carried by one platen, means between the plates for yieldingly holding them apart, one of said plates being adapted to be clamped onto the other by the other platen, and yielding means including a resilient pad between the last mentioned plate and said other platen.

2. In a punch press including relatively movable platens, work clamping means including a pair of plates carried by one platen, means between the plates for yieldingly holding them apart, one of said plates being adapted to be clamped onto the other

by the other platen, and yielding means between the last mentioned plate and said other platen.

3. In a punch press, relatively movable elements, a pivoted punch carried by one of said elements, an abutment carried by the other element, and means on said punch adapted to engage said abutment as said elements are moved together, to rock said punch on its pivot whereby the punch is operable on the work at an angle to the perpendicular.

10 4. A punch press, including relatively movable platens, cooperating punch and

die members carried by said platens, said 15 punch being pivoted on one platen, and means on the other platen for rocking said punch on said pivot into cooperation with said die as said platens are moved toward each other.

20 5. A punch press including a plurality of punches simultaneously operable on a single strip of metal, relatively movable members carrying said punches and said strip, and means for operating one of said punches 25 on the strip at an angle to another punch.

JOHN J. SENGLAR.
